UNITED STATES PATENT OFFICE.

OTTO K. ASCHER, OF ANN ARBOR, MICHIGAN.

DESIGN FOR A CASING FOR FLUSH-TANKS.

SPECIFICATION forming part of Design No. 31,009, dated June 13, 1899.

Application filed May 12, 1897. Serial No. 636,245. Term of patent 31 years.

To all whom it may concern:

Be it known that I, OTTO K. ASCHER, a citizen of the United States, residing at Ann Arbor, county of Washtenaw, State of Michigan, have invented and produced a certain new and original Design for a Casing for Flush-Tanks; and I declare the following to be a full, clear, and exact description of the invention, such as will enable others skilled in the art to which it pertains to make and use the same, reference being had to the accompanying drawings, which form a part of this specification.

Figure 1 is a front elevation of the tank.
15 Fig. 2 is a plan view.

The tank is rectangular in its vertical outline and in horizontal cross-section has a straight back, straight ends, and an irregular front comprising two projecting or columnar parts D and E, between which is a niche or recess C. Each columnar part has the greater part of its front surface plane; but the verti-

cal meeting angles between the plane front surface d or e and the end surface are rounded, as shown at f f', and so also the meeting angle between the inner edge of the plane surface d or e and the surface which joins the face d or e with the face c is rounded, and so also the reentering angle between the face g and the face c is rounded or curved. 25 30

The leading feature of the design consists of the rectangular tank with projecting vertical columns on either side of a recess and between the recess and the ends of the tank.

What I claim is—

The design for a casing of a flush-tank, substantially as described.

In testimony whereof I sign this specification in the presence of two witnesses.

OTTO K. ASCHER.
